Des. 1430

Garrettson Smith & Henry Brown, of Philadelphia, Penn.
Assignors to box Whitman & Box, of same place.
Whole No. 1430, Letters Patent No. 65, dated May 28, 1861.

The schedule referred to in these Letters Patent and making part of the same.

To all whom it may concern;

Be it known that we Garrettson Smith and Henry Brown
of Philadelphia, County of Philadelphia, State of Pennsylvania, have invented or
produced a new and original design for plates of a cooking stove, to which we have
given the name of "Niagara", and we do hereby declare the accompanying drawing,
with the following explanation of the same to form a full clear and exact description of
the said Design.

Fig. 1, of the drawing represents a face view of the upper front plate of the stove.

Dec. 1430

Fig. 2. a view of one of the side plates.

Fig. 3. the back plate.

Fig. 4. a vertical section of the side plate on the line 1. 2.

Fig. 5. the same on the line 3. 4.

Fig. 6. a transverse section of the back plate on the line 5. 6.

The upper front plate of the stove has plain mouldings a. a. and is furnished with two doors A. A. each door being edged with a plain moulding enclosing an ornament b. in the centre of which is a convex boss with scalloped edges.

Above the door is a projecting tablet on which are plain mouldings forming two oblong spaces, the upper space containing the air openings d, and the lower space containing the word "Niagara" in elevated letters.

On each side of the front plate, between the end of the doors and tablet B. and vertical mouldings a. is an ornament c. within which are roughened or rusticated spaces.

The side plate Fig. 2. is edged with a plain moulding a. similar in character to that of the front plate Fig. 1. and is furnished with a large oven door D. and the smaller doors E. and F.

The large oven door is edged with a plain moulding and has an oval convex boss in the centre surrounded by an oval bead, between which a oval moulding f. is a space ornamented with rusticated recesses, the moulding f. being surrounded by an ornament composed partly of foliated, partly of shell like, and partly of denticulated projections as plainly indicated in the drawing, the extent of the projections of these ornaments being shown in the sectional view Fig. 3.

The door E. is edged with a plain moulding inclosing a plain oval bead, having four ornaments, partly foliated, and partly shell like, this oval bead inclosing an annular space with rusticated recesses similar to those of the larger door D. a convex boss with scalloped edges, similar to the bosses on the doors of the front plate being situated in the centre of the door E.

The door F. is so similar in design to this door E. that no description is necessary. The portion of the side plate to which this door F. is hinged projects as seen in the sectional view Fig. 4. one side of this elevated portion of the plate being ornamented with angular pointed ribs x.

Above the large door is an elevated tablet H. with upper and lower edges scalloped, and with foliated ends, the tablet containing in elevated letters the word, Niagara.

Dec. 1430

Near the lower edge of the side plate are three projecting tablets I, J, and K, connected together by foliated ornaments and having upper and lower scalloped edges, one tablet containing, in elevated letters, the word Box, the middle tablet having the words Whiteman & Box, and the remaining tablet the word Philad^a.

The end plate Fig. 3. has a plain moulding A, similar to that of the front plate and has a central ornament M, of a character somewhat similar to the ornament on the large door of the side plate, there being on each side of this central ornament a foliated and scroll ornament N.

I claim the ornamental figures and forms represented in and by the accompanying drawing the whole forming an ornamental design for the front side and back plates of a cooking stove.

In testimony whereof we have signed our names to this specification in the presence of two subscribing witnesses.
